Primary Examiner—C. A. Murphy[57] CLAIM

The ornamental design for an ensemble comprising a dress, socks and gloves for a doll, as shown and described.

DESCRIPTION

FIG. 1 is a front elevational view of an ensemble comprising a dress, socks and gloves for a doll showing my new design;

FIG. 2 is a rear elevational view thereof;

FIG. 3 is a top plan view of the dress component thereof;

being a mirror image;

FIG. 5 is a top plan view of the gloves;

FIG. 6 is a right side elevational view of a glove; and,

thereof, the left side being a mirror image.
